UNITED STATES PATENT OFFICE.

ELMER J. PARDINY, OF CHARLEROI, PENNSYLVANIA, ASSIGNOR TO MACBETH-EVANS
GLASS COMPANY, OF PITTSBURGH, PENNSYLVANIA, A CORPORATION OF PENN-
SYLVANIA.

DESIGN FOR LIGHT-TRANSMITTING GLASS.

Application filed June 24, 1926. Serial No. 18,165. Term of patent 14 years.

To all whom it may concern:

Be it known that I, ELMER J. PARDINY, a citizen of the United States, residing at Charleroi, Pennsylvania, have invented a new, original, and ornamental Design for Light-Transmitting Glass, of which the following is a specification, reference being had to the accompanying drawing, forming a part thereof.

Fig. 1 of the drawing is a front elevation

of a piece of glass showing my new design, and Figs. 2 and 3 sectional views taken, respectively, on the lines II—II and III—III, Fig. 1.

I claim:

The ornamental design for light-transmitting glass as shown.

In witness whereof I have hereunto set my hand this 22d day of June, 1926.

ELMER J. PARDINY.
